UNITED STATES PATENT OFFICE.

LOUIS PELOQUIN, OF SOUTHBRIDGE, MASSACHUSETTS.

BILLIARD CHALK-HOLDER.

1,066,142.

Specification of Letters Patent.

Patented July 1, 1913.

Application filed April 17, 1912. Serial No. 691,333.

To all whom it may concern:

Be it known that I, LOUIS PELOQUIN, a citizen of the United States, residing at Southbridge, in the county of Worcester and 5 State of Massachusetts, have invented a new and useful Billiard Chalk-Holder, of which the following is a specification.

The principal objects of this invention are to provide a billiard chalk holder of simple 10 and inexpensive construction so that it can be made and assembled cheaply and expeditiously and especially to provide an arrangement in which the spring can not become tangled up or otherwise readily get 15 out of order.

The invention also involves other improvements in details of construction as will appear hereinafter.

Reference is to be had to the accompanying drawings in which—

Figure 1 is an end elevation of a chalk holder constructed in accordance with this invention; Fig. 2 is a front view; Fig. 3 is a transverse sectional view on the line 3—3 25 of Fig. 2; Fig. 4 is a central longitudinal sectional view of the drum and connected parts; and Fig. 5 is an elevation of the drum removed from the holder.

The invention is shown in a practical 30 form in which two brackets 10 are applied to the ceiling or other surface on which the holder is to be mounted. With these brackets are connected the ends 11 of a sheet metal frame 12 which constitutes a stationary 35 support for the device. This frame preferably consists of a single piece of sheet metal but can be constructed otherwise if desired. It is of a general cylindrical form, but the surface thereof is discontinued at the top to 40 permit access to the interior parts. It is also provided with inwardly turned flanges 13 at the sides of this cut out portion for a purpose which will appear hereinafter, and it is provided with a vertical downwardly 45 opening, mouth or outlet 14 at the bottom tangent to the circumference of the surface.

Fixedly supported by the sides of this frame is a shaft 16 held in position by screws 17 and provided with an enlarged 50 bushing 18 at the center. Mounted to rotate on this shaft is a drum 20 having open ends, in which are received a pair of coiled springs 21, one end of each spring being connected with the drum and the other with 55 the shaft, whereby, the springs being under tension when the drum is in a certain posi-

tion, they will tend to turn the drum on the shaft for a purpose to be explained hereinafter. At the inner sides of the springs are a pair of flat metal members 22 rotating 60 with the drum and coming against shoulders formed by the ends of the bushing 18. These with the surfaces of the sides 11 assist in holding the springs properly in position if they have any tendency to get out of 65 place. The flanges 13 project over the edges of the drum as is shown so as to constitute guards therefor.

The drum is provided with a key-slot shaped perforation 24 for receiving a knot, 70 projection, or button 25 on the end of a flexible member 26 which may be string, wire, tape, or the like. The projection on the end of this is pushed into the circular part of the slot 24 and then moved longitudinally as indicated, and the flexible member 75 is adapted to be wound up on the drum by the recoil of the springs and to pass down through the passage 14. The end of this flexible connection is connected with the 80 device for holding the chalk. This chalk holder is made preferably as follows:—It consists of two pieces of sheet metal 30 and 31 hinged together by an integral hinge 32 at one corner. Each member consists of 85 three perforated square sides arranged as the three sides of a square in such a way that when the two parts swing together as shown in the drawings the three sides of one part will fill the spaces between the edges of 90 the sides of the other member and form a complete cube or other solid figure. The free end of the member 31 is provided with a perforation 34 for receiving the end of the flexible member 26, and in order to lead this 95 flexible member to this connection and to connect the parts together thereby the member 30 is provided with a perforation 35 through which the flexible member passes.

It will be seen, therefore, that this chalk 100 holder consists simply of a pair of integral sheet metal members hinged together and very simply and economically manufactured, and that the two parts are held together by the action of the springs in the 105 drum. In this way the chalk holder is always kept closed by a spring action both when in use and when not in use, and yet it can be opened very readily for the insertion of a new piece of chalk or for any other 110 purpose.

Although I have illustrated and described

a preferred embodiment of the invention and explained the details of manufacture, I am aware that many modifications can be made therein without departing from the 5 scope of the invention as expressed in the claim. Therefore, I do not wish to be limited to all the details of construction herein shown and described, but

What I do claim is:—

- 10 As an article of manufacture, a device of the character described, comprising a sheet metal frame of substantially cylindrical form having means extending upwardly therefrom for fixing it to a ceiling and a 15 cut out portion at the top extending down-

wardly at one side, a shaft centrally fixed in said frame, a drum rotatably mounted on said shaft, and resilient means for connecting the drum with the shaft, said frame having inturned flanges at its ends overlapping the ends of the drum and coming substantially into contact with the drum near the ends. 20

In testimony whereof I have hereunto set my hand, in the presence of two subscribing 25 witnesses.

LOUIS PELOQUIN.
